Primary Examiner — Sandra L Morris(74) *Attorney, Agent, or Firm* — Bochner IP; Andrew D. Bochner(57) **CLAIM**

The ornamental design for a stuffed animal, as shown and described.

DESCRIPTION

FIG. 1 is a top, front, right side perspective view of the stuffed animal with a zipper in a closed position;

FIG. 2 is a bottom, rear, left side perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is a top, front, right side perspective view of the stuffed animal with the zipper in an open position, illustrating environment;

FIG. 10 is a top, front, right side perspective view with the zipper in an open position; and,

FIG. 11 is bottom view thereof with the zipper in an open position, illustrating environment.

In the drawings, the broken lines are for the purpose of illustrating environment only, and form no part of the claimed design.

1 Claim, 11 Drawing Sheets(56)
